UNITED STATES PATENT OFFICE

CYRUS W. LINN, CLARE G. BIGELOW, AND HARVEY O. RAICHE, OF LANSING, MICHIGAN, ASSIGNORS TO GENERAL MOTORS CORPORATION, OF DETROIT, MICHIGAN, A CORPORATION OF DELAWARE

DOOR CURTAIN

Application filed December 13, 1926. Serial No. 154,487.

This invention relates to improvements in curtains, particularly as applied to motor vehicles. The object of the invention is to construct a curtain which will have considerable rigidity but this rigidity will not be of such a character as to interfere with the relatively easy movement of the vehicle parts, such as the door, with which the curtain is interrelated. It is also an object to construct a curtain which will make a tight joint with its adjacent parts and also afford ample facilities for ventilation. To this end, the curtain incloses a substantially rectangular, noncollapsible steel frame having a limited degree of flexibility. A foldable ventilating flap is applied at the curtain's front edge and at its rear lower corner an opening covered by a flap is provided, the object of which is to allow the chauffeur to extend his hand outside the vehicle.

The curtain is supported at its lower end by brackets mounted in sockets formed in the door and at its upper margin the top is equipped with a valance attached in a novel manner to form a joint and allow ready clashing or folding of the top.

In the drawing:

Figure 1 is a side view of a roadster body illustrating the application of our invention thereto.

Figure 2 is a horizontal section through the curtain and windshield wing on the line 2—2 of Figure 1.

Figure 3 is a similar view but with the front curtain flap folded back to allow for ventilation.

Figure 4 is a vertical section through the curtain on the line 4—4 of Figure 1.

Figure 5 is an enlarged detail from the inside of the vehicle of the shank and ferrule connection between the curtain and the door.

Referring to the drawing, 1 indicates a roadster body to which my invention is shown applied; 2 is the door; 3 the pivoted side

wings of the windshield and 4 the top, all of which are conventional.

Our novel curtain is indicated as a whole at 5, is non-collapsible, and comprises a flexible metal frame 6, sewed in the curtain 5 at 50 its border. The frame 6, is of steel but obviously may be of any suitable material. A one-piece transparent sheet 7, preferably of celluloid, takes up the center portion thereby affording a clear vision, and at its lower 55 border the curtain has affixed thereto the brackets 8, each having a downwardly extending rounded shank 9, and a flat plate like portion 10 through which they are attached to the curtain border and steel frame by 60 means of bolts 11 and nuts 12.

The curtain overlaps the door 2 as shown at 13. At the top 4, the valance 14 is constructed integral therewith, so that the curtain and valance will overlap as shown at 15. 65 The valance 14, is fastened to the top at three points indicated at 16, 17 and 18, of which the fastening 16, is a permanent one and those at 17 and 18 are of the snap type. These fasteners are provided in the valance to allow 70 the top to clash or fold more readily by unfastening the rear end of the valance. At its rear edge, the curtain overlaps the triangular panel 19, as shown at 20, and at its fore edge it is secured to the windshield stanchion 23, 75 by means of tabs 21, having snap fasteners 22, as shown in Figure 2.

In some instances it may be desirable to allow increased ventilation and to this end the fore edge of the curtain is equipped with 80 a flexible flap 24, having upper and lower rows of spaced snap fasteners 25. By releasing the tabs 21, from the fasteners 22, and rolling or folding the flap 24 backward and securing it at one of the series of fasteners 25, 85 a space 26, Figure 3, is allowed for the ingress and egress of air. Obviously, this space may be as wide or narrow as desired within the limits allowed and the control of the circulation of the air may be governed by the 90

angle to which the side windshield 3, is placed. The upper frame member 32 of the door 2, is provided with an opening 27, for receiving a ferrule 28, having a head 29, which rests upon the upper edge of the door. This ferrule is slightly enlarged in the direction of the width of the door, as indicated at 29', by dotted outline in Figure 5, the purpose of which is to accommodate for slight differences in placement of the brackets 8, on the curtain.

10 A left-hand curtain is shown in the drawing and accordingly a triangular opening 30, covered by a flap 31, is provided at its rear lower corner, the object of which is to allow 15 the driver to extend his hand without the vehicle for the purpose of signalling. The hem joint or hinge for the flap is shown at 32' and the overlap of the flap with the curtain is shown at 33. With the arrangement as 20 shown, the flap at the corner has the advantage of being held in closed position by air pressure while the car is traveling.

25 The curtain on the right-hand side is the same as that on the left, except that no flap is provided.

30 It will be understood that various changes in the form, construction, composition and arrangement of the several parts may be resorted to without departing from the spirit 35 and scope of the invention, hence we do not wish to limit ourselves strictly to the structure herein set forth, but—

We claim:—

1. A side curtain for automobiles comprising 40 an integral, noncollapsible, flexible frame sewed in the curtain, brackets secured to the curtain, said brackets having downwardly extending shanks, a door having openings in its upper frame member, sockets in said openings for receiving the shank, said sockets being enlarged in one direction to accommodate for variations in distance between the shanks.

45 2. A side curtain for automobiles, a flexible frame inclosed in said curtain, a foldable extension flap at the front edge of said curtain, fasteners on said flap by means of which it may be removably attached to the windshield stanchion, or secured to the curtain when in folded position.

50 3. In combination with an automobile having a door, a top and a windshield, a valance attached to the top, permanently at its fore end and removably at its rear end and center, a noncollapsible curtain mounted on the door, 55 said curtain overlapping said valance, a foldable flap at the fore edge of the curtain adapted to be removably attached to the windshield, a transparent panel in said curtain, said panel having an opening at one corner, and a flap 60 closing said opening.

4. In combination with an automobile having a door and a top, a curtain between said door and top, said curtain including a frame inclosed within the curtain portion, a bracket 65 rigidly secured to the frame and having a

bent shank portion, means on the door for receiving said shank portion to hold said curtain in operative position, a flap at the fore part of said curtain to close the space between the body of the curtain and the windshield, and tabs on said flap to secure it to the windshield stanchion. 70

In testimony whereof we affix our signatures.

CLARE G. BIGELOW. 75

CERTIFICATE OF CORRECTION.

Patent No. 1,753,795.

Granted April 8, 1930, to

CYRUS W. LINN ET AL.

It is hereby certified that error appears in the printed specification of the above numbered patent requiring correction as follows: Page 2, line 40, claim 1, for the word "shank" read "shanks", and for the word "being" read "having their openings"; and that the said Letters Patent should be read with these corrections therein that the same may conform to the record of the case in the Patent Office.

Signed and sealed this 13th day of May, A. D. 1930.

(Seal)

M. J. Moore,
Acting Commissioner of Patents.
